Attorneys.

UNITED STATES PATENT OFFICE.

WILTON TRIGG, OF CAIRO, ILLINOIS.

CUTTER-HEAD.

SPECIFICATION forming part of Letters Patent No. 292,388, dated January 22, 1884.

Application filed December 12, 1883. (Model.)

To all whom it may concern:

Be it known that I, WILTON TRIGG, of Cairo, in the county of Alexander, and in the State of Illinois, have invented certain new and useful Improvements in Beading and Molding Attachments for Planing-Machines; and I do hereby declare that the following is a full, clear, and exact description thereof, reference being had to the accompanying drawings, in which—

10 Figure 1 shows a view in elevation of a rotary cylinder-planer with my beading attachment applied thereto; Fig. 2, a detail view of the attachment removed, and Fig. 3 a cross-section on line xx of Fig. 1.

15 The object of my invention is to provide an improvement in beading and molding attachments for planers; and to this end it consists in the attachment as hereinafter described, and more specifically set forth in the claims.

20 In the drawings, A designates the cylinder of a rotary planer. To this are attached the cutters or knives B B, slotted at C C, and adjustably held in place on the cylinder by means of set-screws D D, extending through these

25 slots. In the drawings and model these set-screws are shown as provided with washers E E between their heads and the surface of the knife; but such washers are of course not necessary.

30 As is usual in cylinder-planers, the portions of the cylinder between the parts to which the knives are directly attached are cut away or reduced in size, as shown, so that a longitudinal groove, F, is formed in said cylinder be-

35 tween the knives. Within this groove or concave portion of the cylinder-surface is fastened my beading attachment G, consisting of the main attaching part H, curved to fit the groove or concave and slotted, as shown at I,

40 and the portion K extending up in front of and beyond the knife-edge b. The slot in the portion H extends in a direction parallel to the axis of the knife-cylinder. A set-screw, L, provided with washer M, extends through this slot and into the body of the cylinder. With this arrangement of slot and set-screw the beading attachment can evidently be adjusted to a desired position along the cylinder and fixed at any adjustment. As shown, the attachment

50 is curved to fit the concavities in the cylinder—

surface, and so that the beading or molding end rests against the under surface of the knife, near and at the edge of the latter, and is thus supported by it and prevented from being bent back when the planer is in operation. I contemplate using a series of these beading attachments on the same cylinder, but prefer to have each attachment in a different groove in the cylinder, and acting directly with a different knife, as indicated in the drawings. The shape 60 of the operative end of the attachment, which projects beyond the edge of the knife, is of course to be of any form desired to make any particular shape of molding or beading.

55 I have shown my attachment as applied to a cylinder-planer. It obviously can be equally well applied to other forms of planers in the same way without departing from my invention.

Having thus fully set forth the nature of my 70 invention, what I claim is—

1. In combination with the planer, the beading or molding attachment attached to said planer in front of a cutter thereof, and supported near its operative end, which projects 75 beyond the edge of the cutter, by the under face of said cutter, substantially as shown and described.

2. In combination with the cutter of a planer, a beading or molding attachment fastened upon the surface of the planer in front of the cutter, and at its operative end bent up, so as to rest against the under face of the latter and be supported thereby, substantially as and for the purpose described.

3. In combination with a planer, a beading attachment adjustably fastened upon the planer in front of a knife, and at its operative end supported by the under face of the knife, substantially as and for the purpose set forth.

4. In combination with the planer-cylinder, the beading attachment adjustably fastened to the cylinder in front of one of the knives by means of a set-screw passing through a slot in its attaching portion, and supported at or near 95 its operative end by the knife, substantially as shown and described.

5. In combination with the cylinder, concaved or provided with longitudinal grooves between the knives, the beading attachment 100

adjustably fastened within one of said grooves, and at its operative end bent up, so as to bear against and be supported by the under face of the knife on the rear side of the groove, substantially as and for the purpose set forth.

6. In combination with the grooved cylinder carrying the cutter-knives, the beading or molding attachment having its main or attaching portion bent to fit the concavity of the groove, and provided with the slot extending parallel to the axis of the cylinder, and the set-

screw extending through such slot into the cylinder-body, substantially as and for the purpose set forth.

In testimony that I claim the foregoing I 15 have hereunto set my hand this 27th day of October, 1883.

WILTON TRIGG.
